UNITED STATES PATENT OFFICE.

ROSE F. BRACCO, OF CHICAGO, ILLINOIS.

SATCHEL CLIP.

Application filed February 23, 1922. Serial No. 533,611.

To all whom it may concern:

Be it known that I, ROSE F. BRACCO, a subject of the King of Italy, and a resident of Chicago, in the county of Cook and State 5 of Illinois, have invented new and useful Improvements in Satchel Clips, of which the following is a specification.

The present invention has relation to satchels, hand bags, wrist bags and similar 10 articles, particularly such as the shopping bags commonly carried by women, and which usually contain their valuables, purses and the like.

The usual type of locking means applied 15 to such bags is a pair of interlocking knobs on slender stems and the resiliency of the frame parts, to which these knob stems are secured, is depended upon to permit the knobs to pass each other in locking and in 20 unlocking the bag. But in spite of the resiliency of the frame parts it is found that the pressure on the knobs, during the opening and closing operations is sufficient gradually to bend the stems back to such an ex- 25 tent that the interlocking knobs first become insecure and later entirely incapable of holding the bag closed. Frequently, also, one of the knobs will break away from its fastening, causing the owner much inconvenience 30 and expense.

With the foregoing conditions in view the object of my invention is the provision of means, attachable to a bag of the kind specified, for locking such bag securely where the 35 fixed locking devices have become unreliable or entirely useless. A further object is to provide a neat and inexpensive device attachable to various sizes and shapes of such bags. Another object is to provide a device which 40 may be readily attached to any such bag without the use of extraordinary skill or special tools. These objects and the further advantageous features of my invention are hereinafter fully set forth and illustrated in 45 the accompanying drawing, of which,

Fig. 1 is a fragmentary perspective view of a lady's wrist bag embodying the invention.

Fig. 2 is a cross-sectional end elevation of 50 the bag, substantially taken on a line A—A of Fig. 1.

Fig. 3 illustrates my locking device as it appears removed from the bag, and

Figs. 4 and 5 show modified structures of 55 my invention.

The bag shown in the drawing is meant

to represent the type almost universally carried by women, young and old. The bag proper is identified by the numeral 1, and it is supported by a pair of frames 2 and 3, the 60 outer extremities of which are hinged together, as indicated at 4 in Fig. 2. A pair of locking knobs 5 and 6 are centrally placed on the frames through the medium of slender stems 7, and 8, substantially as in practice. Usually these stems are merely soldered to the frame pieces, and very easily broken off, particularly when they are bent back a little and the owner tries to force 65 them forward into their original shape and sets them too far over. The reason underlying this difficulty is, of course, that the stems are not elastic enough to retain their shape during the ordinary hard usage.

The structure of my invention, as applied 70 to the bag, comprises a resilient clip 10, carried by a flexible member 11, which is caused to extend through the material of the bag, within which it is secured by means of a suitable clamp 12. The clip is strong and 75 elastic and sets over the frame parts 2 and 3, extending below these parts, where the arms of the clip turn inward, causing the extremities 10^a, 10^b of the clip to press 80 against the material of the bag, substan- 85 tially as indicated in Fig. 2. The clip, as stated, is strong and elastic, yet not so strong that it cannot readily be forced into position or withdrawn from the bag frame as desired. But while it readily yields to longitudinal pressure it will tenaciously resist 90 transverse pressure, such as an attempted opening of the bag would subject it to.

The clip is shown hung on a chain 11, and this is the preferred form of a suspension means, both on account of its strength and flexibility and also because its pleasing appearance adds to the attraction of the device. The opposite end of the chain is fastened to the bag, preferably by projecting 95 the end of the chain through the bag material, and by applying suitable elements to the end of the chain, within the bag, capable of retaining the chain in place. It does not greatly matter as to what shape 105 such anchoring devices are given, so long as they function properly, so long as they are not obstructive within the bag or unpleasant for the fingers to come into contact with, and so long as they do not detract 110 from the appearance of the bag.

A simple device is shown in the drawing,

comprising merely the bent wire 12, a structure so commonly used in detachable buttons that no further explanation is thought necessary. But it may be objected that this 5 fastening means is not sufficiently pleasing, in which case I may substitute the somewhat more elaborate device of Figs. 4 and 5. This device comprises a clasp 13, such as commonly used on watch chains, and a 10 button 14 provided with a rigidly affixed eye 15. As shown in Fig. 5, the eye 15 is first projected from the inside through the material of the bag, whereupon the clasp 13 is hooked into the eye and the structure is 15 firmly held in place.

The clip of my device may be made from 20 spring steel or brass, and I contemplate, of course, not only to make it plain, as shown, but also ornamental and more expensively 25 finished in order to please those who prefer to pay a higher price for a more elaborate device. And it is not necessary that the clip must be made from sheet metal, as indicated, it may indeed be made from any other suitable shape and kind of material, so long as 30 it performs its function properly. Clips held together by a coil-spring are very common in paper fasteners, and may be employed if they are found to lock the bag securely, or a wire clip 20, substantially as 35 shown in Fig. 4, may conveniently be used. In this case a piece of spring wire is formed with a small loop 20^a, in which the chain 21 is mounted, and the ends of the wire may conveniently be formed into eyes 20^b, 20^c for

the purpose of obtaining a firmer hold on the bag, and also in order that no dangerous sharp points may be present.

Now it may be suggested that auxiliary means have heretofore been known for 40 maintaining a shopping bag locked, but such means as have come to my notice have been shown pivotally fixed on the bag frame, thereby forming a permanent part of the frame. When such means becomes broken 45 or bent out of shape, it still forms an unsightly part of the frame, and the utility of the bag is impaired. But the structure of my invention is an independent commercial article, obtainable at small cost and attachable to any such bag. When it is worn out or broken it can be as readily taken off and a new one substituted.

I claim:

1. The combination with a shopping bag 55 of a clip, a chain extending from said clip for projection through the material of the bag, and a member within the bag for engagement with the projecting end of said chain.

2. The combination with a shopping bag 60 of a detachable bag frame embracing member, a resilient member extending from said clamping member, and a member insertable into the bag for attachment through the bag material with one end of said resilient member.

In testimony whereof, I have hereunto affixed my signature.

ROSE F. BRACCO.
